EXPANSIBLE WIPING DIE

Joseph E. Lodge, Baltimore, Md., assignor to
Western Electric Company, Incorporated, New
York, N. Y., a corporation of New York

Application May 24, 1946, Serial No. 672,031

6 Claims. (Cl. 91—53)

1

This invention relates to expandible wiping dies, and more particularly to expandible wiping dies for wiping excess coating material from coated filamentary articles.

In coating filamentary articles, such as insulated conductors, it is often necessary to apply an excess amount of coating material to the articles and then wipe off the excess. Some dies for wiping the excess coating material from filamentary articles are expandible in order to accommodate themselves to varying cross-sectional sizes of filamentary articles, and to permit spliced or knotted portions of the articles to pass therethrough without manually adjusting the dies to permit them to pass through the dies. With dies heretofore known, it has been difficult to advance knotted or spliced portions of filamentary articles therethrough without snagging.

An object of the invention is to provide new and improved expandible dies.

A further object of the invention is to provide new and improved expandible dies for wiping excess coating material from filamentary articles and for permitting knots, splices and the like to be drawn through the dies.

An expandible die forming one embodiment of the invention includes a pair of separable die sections having a passage therein. A frame having a rectangular opening therein engages a face and sides of one of the die sections near the center portions thereof and slidably engages the sides of the other die section near the center portions thereof. A presser having a bevelled end engages the face of the last-mentioned die section near the center portion thereof and permits that die section to be moved away from the other die section and to be pivoted with respect to the other die section about an axis transverse to the passage in the die sections so that the passage in the die section may be expanded in increments along the longitudinal axis.

A complete understanding of the invention may be obtained from the following detailed description of expandible dies forming specific embodiments thereof, when read in conjunction with the appended drawings in which:

Fig. 1 is a fragmentary, top plan view of a coating apparatus and a die assembly forming one embodiment of the invention;

Fig. 2 is a fragmentary, vertical section taken along line 2—2 of Fig. 1;

Fig. 3 is an enlarged, fragmentary, top plan view of the apparatus shown in Fig. 1;

Fig. 4 is an enlarged, fragmentary, vertical section taken along line 4—4 of Fig. 3;

2

Fig. 5 is an enlarged, fragmentary, vertical section taken along line 5—5 of Fig. 3;

Fig. 6 is an enlarged, fragmentary, horizontal section taken along line 6—6 of Fig. 5;

Fig. 7 is an enlarged, fragmentary, vertical section similar to Fig. 5 of an expandible die forming an alternative embodiment of the invention, and

Fig. 8 is an enlarged, fragmentary, vertical section taken along line 8—8 of Fig. 7.

Referring now in detail to the drawings, a coating apparatus forming one embodiment of the invention includes a tank 10 (Fig. 1) having a supply of weatherproofing material therein. Grooved coating discs 11—11 are mounted on a shaft 12 rotatably mounted in bearings, illustrated by a bearing 15, and coat insulated conductors 16—16 with an excessive amount of the weatherproofing material as the conductors are advanced through the grooves therein. A gang wiper 19 serves to wipe the excess weatherproofing material from the insulated conductors 16—16, and the excess weatherproofing material wiped from the insulated conductors drains back into the tank 10.

The gang wiper 19 includes identical die assemblies 20, 21, 22 and 23, and is mounted on a wall 25 of the tank 10. The gang wiper includes a support 26 having slots 27—27 in the ends thereof, which is bolted adjustably to spacers 28—28 fastened to the wall 25 to the tank 10. The support 26 has upwardly facing horizontal grooves 30, 31, 32 and 33 (Fig. 3) and also is provided with vertical guideways 35, 36, 37 and 38, which are transverse to the horizontal grooves 30, 31, 32 and 33, respectively. Each of the die assemblies 20, 21, 22 and 23 is identical with the others, and, for purposes of simplicity only the die assembly 20 will be described. The die assembly 20 includes an eyelet frame 40 (Fig. 4) having a rectangular opening 41 formed therein and a threaded rod 42 projecting from the upper portion thereof, as viewed in Fig. 5. A nut 43 and a spring retainer seat 44 retaining a compression spring 45 on the rod 42, and the compression spring 45 urges a split presser 46 having bevelled edges 47—47 against a die section 50 of a die 52 at portions of the die section 50 slightly to the right of the center thereof, as viewed in Fig. 5. This urges the die section 50 against a die section 51, which is complementary thereto, and holds the die section 51 against the frame 40.

The die section 50 is provided with a bell-mouth entrance portion 55 of a groove 56 therein. A large groove 57 concentric with the groove

56 serves to receive a liner 60 of a high carbon steel, which is highly resistant to wear. A retaining plate 61 having a groove 62 therein is positioned in a slot 63 in the die section 50, and retains the liner 60 in the large groove 57 in the die section 50. The die section 51 is identical with the die section 50 and includes a bell-mouth entrance portion 65 of a groove 66 formed therein and a large groove 67 corresponding to the large groove 57 on the die section 50. A liner 70 of high carbon steel is retained in the large groove 57 in the die section 51 by a retaining plate 71, which has a groove 72 therein and is secured in a slot 73 formed in the die section 51. An abutment 75 formed on the support 26 and having a plurality of passages, illustrated by a passage 76, therein prevents movement of the die sections 50 and 51 toward the right, as viewed in Fig. 5.

The die section 51 is provided with fluted portions 80-80 separated from the passage 20 proper therein by narrow lands 81-81, and the die section 50 is provided with similar fluted portions (not shown) and narrow lands (not shown) identical with the fluted portions 80-80 and the narrow lands 81-81, respectively. The narrow lands prevent accumulation of material therebetween so that pressure of the material therebetween will not prevent closing of the die sections. Relieved portions 35-35 (Fig. 4) of the groove 35 provide clearance for movement of the die section 50 and for escape of excess coating material. The opening 41 in the eyelet frame 40 is wider than the die sections 50 and 51 so that it does not obstruct escape of excess material. The clearance of the groove 35 and the frame 40 also prevents binding between these elements. The conductor 16 traveling through the liners 60 and 70 aligns the die section 50 with the die section 51 inasmuch as the die section 50 is pressed towards a closed position. A rounded end 86 of the die section 50 permits pivotal movement thereof.

In the operation of the coating apparatus described hereinabove, the insulated conductors 16-16 are advanced over the grooved coating discs 11-11 which are rotated by the shaft 12 and dip into the weatherproofing material in the tank 10. This coats the conductors 16-16 with an excess of weatherproofing material. The conductors 16-16 travel from the coating discs 11-11 to and through the die assemblies 20, 21, 22 and 23, which wipe the excess weatherproofing material from the insulated conductors. The die assemblies are expansible so that they may conform themselves to varying cross-sectional sizes of the conductors 16-16 and permit knots, spliced portions and the like of the insulating conductors 16-16 to be advanced therethrough without manually separating the die sections thereof.

When a knot or a spliced portion in the insulated conductor 16 being advanced through the wiping die assembly 20 enters the bell-mouth portions 55 and 65 of the die sections 50 and 51, respectively, it pivots the die section 50 in a clockwise direction, as viewed in Fig. 5, about the end of the presser 46, which engages the die section 50 at a point to the right of the central portion of the die section 50. As the knot or spliced portion is continuously advanced through the die 52, the die section 50 is raised away from the die section 51 so that the passage in these die sections is enlarged. Due to the pivotal action of the die section 50 with respect to the die section 51, the passage formed by

5 these die sections may be easily expanded without any danger of breaking the conductor when a knotted or spliced portion of the conductor is advanced through the die 52. The presser 46 normally maintains the die sections 50 and 51 in close engagement with each other and any excess weatherproofing material on the insulated conductor 16 is wiped therefrom along the entire portion of the insulated conductor in the die 52. The weatherproofing material wiped from the insulated conductor in the grooves 56 and 66 and liners 60 and 70 in the die 52 escape easily over the narrow lands 81-81 of the die section 51 into the fluted portions 80-80 therein so that force does not build up between the junction line of the two die sections. The retaining plates 61 and 71 block any flow of the weatherproofing material toward the right ends, as viewed in Fig. 6, of the fluted portions, illustrated by the fluted portions 80-80.

The die assemblies 20, 21, 22 and 23 normally press tightly against the insulated conductors 16-16 and effectively wipe any excess of weatherproofing material from the insulated conductors. The dies of the wiper 49 may be easily expanded so that knots or other enlarged portions of the insulated conductors 16-16 may be advanced through the dies without danger of becoming snagged thereon. Thus, any danger to the insulated conductors from breaking thereof is eliminated.

A gang wiper 119 (Fig. 7) forming an alternative embodiment of the invention is mounted on an end wall 125 of a tank 110 similar to the tank 10 (Fig. 1). The gang wiper 119 (Fig. 7) includes a plurality of die assemblies, illustrated by a die assembly 120, which are mounted on a support 126 adjustably mounted on the end wall 125 of the tank 110 on spacers, of which a spacer 128 is shown. The support 126 includes an abutment shoulder 175 having passages illustrated by a passage 176 formed therein to permit insulated conductors to be advanced therethrough. The support 126 also is provided with bores, illustrated by a bore 136, and vertical guideways, illustrated by a vertical guideway 135, and an eyelet frame 140 of the die assembly 120 having a rectangular opening 141 therein is mounted slidably in the guideway 135 formed in a support 126. The opening 141 (Fig. 8) in the eyelet frame 140 is wider than the die sections 150 and 151 so that they may float laterally therein and so that the die section 151 does not bind therewith. The die section 151 is provided with a rounded end 186 to facilitate its pivotal movement.

A threaded rod 142 projecting from the eyelet frame 140 is mounted slidably in a bore 136 in the support 126, and a compression spring 145 is positioned over the rod 142 and is retained thereon in engagement with the support 126 by a spring retainer seat 144 mounted adjustably on the rod 142 by a nut 143. The compression spring 145 urges the rod 142 and the eyelet frame 140 upwardly, as viewed in Fig. 7, and a bevelled edge 149 of the frame 140 engages a die section 151 of a die 152 at a point to the right of the center thereof, and normally holds the die section 151 in engagement with a die section 150.

In the operation of the gang wiper 119, the conductors are passed through the dies, illustrated by the die 152, and the excess weatherproofing material is wiped therefrom. When an enlarged portion of the insulated conductor travels through the die 152, it first pivots the die section 151 in a

counterclockwise direction, as viewed in Fig. 7, about the bevelled edge 149 of the frame 140 and moves the frame 140 downwardly against the action of the compression spring 145. As the enlarged portion of the insulated conductor travels farther to the right, as viewed in Fig. 7, the die section 151 is moved farther away from the die section 150 to permit the enlarged portion of the insulated conductor to be advanced through the die 152. After the enlarged portion of the insulated conductor travels completely through the die 152, the frame 140 moves the die section 151 back against the die section 150 and the wiping operation is resumed.

The gang wiper 119 effectively wipes excess weather-proofing material from insulated conductors advanced therethrough, but permits enlarged portions, such as knots or splices, of the insulated conductors to be advanced through the expansible dies thereof without breaking the insulated conductors and without stopping the travel of the insulated conductors in order to adjust the gang wiping die assembly 119 whenever an enlarged portion of one of the insulated conductors is to be advanced through one of the dies thereof.

What is claimed is:

1. An expansible die, which comprises a pair of elongated die sections having an elongated passage formed therein a support having a socket therein, a frame designed to fit into the socket and having an opening therein for engaging one of the die sections along a line near the central portion of that die section and for limiting lateral movement of the die sections, the thickness of the frame being substantially less than the length of the die section to prevent binding between the frame and the die sections, and a presser urged against the other die section near the central portion of that die section for urging the die sections together and for permitting pivotal movement of the last-mentioned die section about an axis perpendicular to the longitudinal axis of that die section.

2. An expansible die, which comprises a pair of elongated, separable die sections having a passage formed therein, a support having a socket therein, a frame designed to fit into the socket and having a rectangular opening for receiving the die sections therein, said frame serving to engage a face of one of the die sections near the central portion thereof and being substantially thinner than the length of the die sections, and a presser having a bevelled end for engaging the face of the other die section near the central portion thereof to urge the die sections together.

3. An expansible die, which comprises a pair of elongated die sections having an elongated passage therein, a support, a thin frame having an opening therein for bracketing the die sections, and means for urging the frame toward the support in such a direction as to hold one of the die sections against the support and to permit pivotal movement of the other die section with respect to the die section held against the support, said frame serving to restrict lateral movement of the die sections.

4. An expansible die, which comprises a pair of

elongated die sections having a predetermined combined thickness, a support having a guideway therein, a frame having an opening therein for receiving the die sections, and being slidably mounted in the guideway in the support, one dimension of the opening in the frame being substantially greater than the combined thickness of the die sections, and means for urging the frame through the guideway in the support to urge the die sections together and toward the support.

5. An expansible die, which comprises a plate having a guideway extending transversely therethrough, an elongated die section for fitting against one face of the plate in a centered position with respect to the guideway, a second elongated die section forming a die with the first-mentioned die section, said die sections having a predetermined combined thickness, a frame mounted slidably in the plate and being provided with a pair of arms for bracketing the die sections to limit lateral movement of the die sections, said arms being substantially longer than the combined thickness of the die sections, said frame also having a bar extending between the arms thereof for engaging the second-mentioned die section, means for urging the frame through the guideway to urge the second-mentioned die section against the other die section and the latter die section against the support, and means for limiting endwise movement of the die sections.

6. An expansible die, which comprises an L-shaped support having a groove formed in the inside portion of one arm of the support from the outer edge of that arm to the inner edge thereof and also being provided with a rectangular guideway extending through that arm of the support transversely to the groove and being centered with respect to the groove, an elongated die section designed to seat in the groove, a second elongated die section forming a die with the first-mentioned die section, said die sections having a predetermined combined thickness, an eyelet bolt mounted slidably in the guideway, the opening of the eyelet bolt being substantially greater in its dimension parallel to the longitudinal axis of the guideway than the combined thicknesses of the die sections and serving to receive the die sections, a spring seat mounted on the eyelet bolt, and a spring mounted on the eyelet bolt between the support and the spring seat for urging the bolt through the guideway to press the die sections together.
